Application February 18, 1948, Serial No. 9,079

9 Claims. (Cl. 254—187)

1

This invention relates to hand-operated winches and particularly to swing stage winches used primarily for raising and lowering swinging scaffolds.

Swing stage winches employing three separate safety devices comprising, a self-locking brake interposed in the drive mechanism between the crank handle and the cable drum, a pawl biased to engagement with a ratchet mounted on the cable drum, and a stop mechanism to prevent movement of the crank handle in the unwinding direction, have been proposed. Winches of this type may be seen in the co-pending application of Nelson et al. Serial No. 764,828, now abandoned, assigned to applicant's assignee, or in Benson, Patent No. 2,424,910. While the structures shown in the Nelson et al. application and in the Benson patent provide desirable safety features, they are, nevertheless, open to improvement.

The present winch is an improvement over the structures shown by Nelson et al. and by Benson. The swing stage winch according to this invention is a light, compact winch having the brake and gear mechanism enclosed in a sealed compartment which prevents undue wear due to foreign matter. Furthermore, the handle stop mechanism may be employed at any time, and the brake mechanism may be disengaged to permit cable to be stripped from the drum rapidly but the winch may not be used for raising or lowering during such time as the brake mechanism is disengaged.

Accordingly, an object of this invention is to provide a light, compact, hand-operated winch which may be readily handled by one person.

Another object is to provide a winch having gears and a self-locking brake mechanism enclosed in a sealed compartment providing for better lubrication and freedom from foreign material.

A further object is to provide a hand operated winch having three separate mechanical safety devices which are so inter-related as to greatly facilitate operation.

A further object is to provide a simple method for disengaging the self-locking brake mechanism so that cable may be pulled freely off the drum and yet prevent winding of the cable on the drum while the brake is disengaged.

Other objects and advantages will be pointed out in, or be apparent from, the specification and claims, as will obvious modifications of the single embodiment shown in the drawings in which:

2.

Fig. 1 is a side elevation of the winch with parts broken away;

Fig. 2 is a front elevation in section taken along line 2—2 of Fig. 1 with parts broken away;

Fig. 3 is a front elevation of Fig. 1 taken along line 3—3 showing the drum pawl and handle stop in two positions;

Fig. 4 is a section view of Fig. 1 taken along line 4—4 showing the spider mounting for the planetary gears shown in dotted lines;

Fig. 5 is a section taken on line 5—5 of Fig. 1 and shows the shaft pin cooperating with the land inside the handle for limiting relative movement between the shaft and the handle; and

Fig. 6 is a fragmentary section of the brake parts as viewed in Fig. 1 but has the handle removed and the brake mechanism locked so cable may be stripped from the drum.

Referring to the drawings in detail, drum shaft 10 is non-rotatably mounted in frame 12 by means of two cap screws 14, 14. Since frame 12 carries at its lower end stirrup 16 (only part of which is shown) for the usual scaffold platform, the frame and drum shaft 10 are fixed with respect to the moving parts of the winch mechanism. Cable drum 18 is rotatably mounted on bearings 20 on both ends of drum shaft 10 and carries on its right-hand peripheral edge, as viewed in Fig. 1, a ring 22 having gear teeth 24 on the inside and ratchet teeth 26 formed on the outside. On the right-hand end of drum shaft 10 is an integral three-prong spider 28. Each of the prongs carries planetary gear 30 rotatably mounted on bearing 32 mounted on pin 34. The planetary gears 30 are restrained from axial movement on pins 34 by means of washers 36 which are held in place by retaining ring 38. Pawl 40 is mounted on the right-hand end of pin 34 and is biased by spring 42 into engagement with brake idler ratchet disk 44 which will be more fully described hereinafter.

The planetary gears 30 engage ring gear 24 and sun gear 46 which is carried by shaft 48. The left-hand end of shaft 48 is rotatably mounted in bearing 50 in hole 52 in the central portion of the three-pronged spider 28. The right-hand portion of shaft 48 has screw thread 54 formed thereon. A brake flange 56 is threadably mounted on shaft 48 adjacent sun gear 46 to form an integral part of shaft 48 and loosely carries ratchet disk 44 on the right-hand stepped face thereof. A handle fitting 58 engages the right-hand portion of the thread 54 and shaft 48 and is rotatably mounted in bearing 60 which provides a seat for a cover plate 62 and is rigidly

mounted in frame 12. Cap screws 64 hold cover plate 62 and ring 22 firmly on drum 18 for rotation therewith. The crank handle 66 is retained on handle fitting 58 by means of thumb screw 68. As viewed in Fig. 1, the large end of thumb screw 68 is screwed into handle 66 and pin portion 70 of screw 68 snugly fits within the cooperating hole in the handle fitting 58 but does not contact shaft 48.

When handle 66 is rotated in a clockwise direction, as viewed in Fig. 3 (when the handle is moved toward the viewer in Fig. 1) handle fitting 58 will move to the left on shaft 48 until the handle fitting forces ratchet disk 44 against brake disk 56 to provide frictional engagement between the parts. When the slack is thus taken up, there is a direct drive through the brake mechanism, and the sun gear will be rotated in a clockwise direction. Since planetary gears 30 are rotatable about their own axes, but not about the central axis, their rotation will be counter-clockwise causing counter-clockwise rotation of the cable drum to raise the winch and scaffold. If handle 66 is now moved in a counter-clockwise direction, handle fitting 58 will move to the right so there is no longer a frictional engagement in the brake mechanism. This will permit cable to unwind from the drum until the sun gear and shaft 48 are rotating at such a speed that fitting 58 will move to the left on the threads 54 until frictional engagement in the brake is again obtained. At this time, if the handle movement has ceased, the pawls 40 engaging ratchet disk 44 lock the drum against rotation.

It will be apparent that if some means were not provided for preventing excessive movement of handle fitting 58 to the right the fitting would eventually abut against and bind with bearing 60. Therefore, the outer end of shaft 48 is provided with a pin 72 which cooperates with land 74 on the inside of the handle socket (see Fig. 5) to limit movement of the handle fitting with respect to the shaft and thus prevent binding between the fitting and bearing surface 60.

On spacer bar 76 provided in the lower portion of frame 12 is mounted pawl 78 which is biased by tension spring 80 into engagement with ratchet gear 26 formed on ring 22. Mounted between pawl 78 and the right-hand portion of frame 12 is a handle stop 82 which has a finger 84 normally in the path of lug 86 on handle 66, so lug 86 will abut finger 84 and prevent rotation of the handle in the unwinding direction unless the stop 82 is lifted upwardly out of the path of rotation. Stop 82 is biased by gravity into the position shown in solid lines in Figs. 2 and 3 where the finger 84 rests against frame 12. On the left-hand portion of stop 82, as viewed in Fig. 1, is another finger 88 which is adapted to strike the free end 90 of pawl 78 so the operator, when lifting stop 82 out of the path of handle rotation, merely has to raise the stop until it strikes free end 90 to rotate the pawl 78 about spacer bar 76 until it no longer engages ratchet teeth 26. The solid line position of pawl 78 and stop 82, as shown in Fig. 3, indicates the position for preventing cable unwinding, and the dotted line position shows the pawl and stop in the position occupied during the unwinding operation.

Operation

To raise the scaffold and winch or to wind cable onto the drum 18, handle 66 is rotated in a clockwise direction to move handle fitting 58 to the left until ratchet disk 44 binds with brake disk 56 and

the fitting to obtain a frictional drive through the brake mechanism. At this time the sun gear will be rotated in a clockwise direction and drive ring gear 24 and drum 18 in a counter-clockwise direction through the planetary gears and wind cable on the drum. During this time stop 82 may be moved upwardly by the operator out of the path of lug 86 on handle 66 or may merely be moved aside by the lug striking finger 84 with each revolution. If the latter procedure is followed, the stop will always be available as a safety factor to prevent counter-clockwise movement of the handle. While the cable is being wound onto the drum, pawl 78, which is spring-loaded into engagement with ratchet 26, will merely ride over the teeth, but will act to prevent rotation immediately upon any tendency of the drum to reverse direction of rotation. The spring-loaded pawls 40 mounted on the planetary shafts 34 will also ride over the teeth on disk 44 but will be in operative position at all times to prevent reverse rotation of shaft 48.

To hold the scaffold at any desired position, pawl 78 engages ratchet teeth 26 to hold the drum against rotation while pawls 40 engage ratchet disk 44 to also hold the drum against rotation. Similarly stop 82 is in position due to the force of gravity to stop counter-clockwise rotation of handle 66.

To lower the scaffold or unwind cable from drum 18 stop 82 is raised until it strikes free end 90 of pawl 78 and moves the pawl out of engagement with ratchet teeth 26. At this time pawls 40 engaging disk 44 hold the drum against rotation. If the handle 66 is now rotated in a counter-clockwise direction, fitting 58 will move to the right (Fig. 1) until it is no longer in frictional engagement in the brake mechanism. This will now allow the drum to move in a clockwise direction and allow cable to unwind from the drum until the threads 54 on shaft 48 rotate faster than fitting 58 and screw into the fitting to move it back to the left to regain the frictional engagement. At this time the pawls 40 hold the disk 44 against rotation and consequently stop the drum rotation. It should be noted here that if the operator should lose his grip on handle 66 the automatic locking brake mechanism will prevent cable from unwinding. However, if handle 66 is continually rotated in a counter-clockwise direction, the frictional engagement in the brake mechanism will make and break at intervals dependent upon the speed of rotation of handle 66 to lower the scaffold in what actually amounts to a series of steps. Should it become necessary for any reason to utilize the additional safety features, the operator merely has to release stop 82 to allow tension spring 80 to bring pawl 78 into engagement with ratchet teeth 26 and to allow finger 84 on the stop to move into the path of rotation of lug 86 on handle 66.

When it is desired to strip cable freely from the drum, the handle is rotated in a counter-clockwise direction to move fitting 58 to the right out of engagement with disk 44. It should be noted that stripping the cable from drum 18 presupposes that there is no load on the cable, for if the cable were loaded the brake mechanism would immediately proceed to lock as set forth above. However, with no load on the cable, the fitting 58 may be moved to the right and retained there while thumb screw 68 is unscrewed from fitting 58 and handle 66 to permit the handle to be removed from the fitting. The small

end 92 of thumb screw 68 is now screwed into fitting 58 at a point approximately diametrically opposed to the hole which pin 70 fitted. The thumb screw 68 is turned into the threaded hole in fitting 58 to engage shaft 48 and prevent axial movement of the fitting with respect to the shaft. This retains the brake mechanism in its inoperative or disengaged position, and cable may now be pulled from drum 18 without the brake moving to frictionally engage again. Placing the holes in fitting 58 on opposite sides of shaft 48 and threading but one hole insures against the operator attempting to utilize the winch for raising and lowering while the brake is held from engagement. When it is desired to transport or handle the winch on the ground, it is desirable to have some means to prevent cable unwinding from the drum. For this purpose cable hook 94 is mounted on the left-hand side (Fig. 1) of frame 12 so the customary loop at the end of the cable may be placed under the hook and the slack then taken up by turning handle 66.

It will be evident that I have provided a simple compact winch having a planetary gear transmission and a self-locking brake mechanism which is both simple to operate and maintain and is completely enclosed within a sealed chamber defined by one side of drum 18, ring 22, and casing cover 62. It will be evident that the gear ratio may be changed to give different mechanical advantages and rates of ascent and descent. In addition to the self-locking brake, there is provided a pawl engaging the drum and a stop engaging handle 66. All of these safety devices act at all times to prevent rotation of the drum in the cable unwinding direction, and the stop is so related with respect to the drum pawl that the single movement of the stop upwardly about its axis will automatically move drum pawl 78 from engagement with the drum ratchet. The brake mechanism may be rendered inoperative by removing thumb screw 68 and screwing it in the other side of the handle fitting 58 to hold the fitting axially fixed with respect to shaft 48. It will be evident that other means could be provided for disengaging the brake mechanism, but the above structure is preferred since it requires complete removal of the handle and prevents negligent operation of the winch. Similarly other modifications of this winch structure will occur to those skilled in the art. Accordingly, I do not wish to be limited in my invention except by the scope of the claims.

I claim:

1. In a hand-operated winch, a frame having a winding drum rotatably mounted therein, a ring gear fixed with respect to the drum, a shaft having a sun gear fixed thereon, a pin having a planetary gear mounted thereon in engagement with said sun and ring gears, a portion of said shaft being threaded, a self-locking brake mechanism mounted on said shaft and comprising a brake disk carried by said shaft, a handle fitting threadedly engaging the threaded portion of said shaft, a ratchet disk between said brake disk and said handle fitting, the pitch of said threaded portion being adapted to move said fitting into frictional engagement with said disks in response to a force tending to unwind cable from the drum, a pawl biased into engagement with said ratchet disk to prevent rotation thereof in the cable unwinding direction.

2. In a hand-operated winch, a frame having a winding drum rotatably mounted therein, a ring gear fixed with respect to the drum, a shaft

having a sun gear fixed thereon, a pin having a planetary gear mounted thereon in engagement with said sun and ring gears, a portion of said shaft being threaded, a self-locking brake mechanism mounted on said shaft and comprising, a brake disk carried by said shaft, a handle fitting threadedly engaging the threaded portion of said shaft, a ratchet disk between said brake disk and said handle fitting, the pitch of said threaded portion being adapted to move said fitting into frictional engagement with said disks in response to a force tending to unwind cable from the drum, a pawl biased into engagement with said ratchet disk to prevent rotation thereof in the cable unwinding direction, a handle for actuating said sun gear through said brake mechanism, means connecting said handle to said fitting, said connecting means being adapted to lock said disks and fitting with respect to each other.

3. In a hand-operated winch, a frame having a winding drum rotatably mounted therein, a ring gear fixed with respect to the drum, a shaft having a sun gear fixed thereon, a pin having a planetary gear mounted thereon in engagement with said sun and ring gears, a portion of said shaft being threaded, a self-locking brake mechanism mounted on said shaft and comprising, a brake disk carried by said shaft, a handle fitting threadedly engaging the threaded portion of said shaft, a ratchet disk between said brake disk and said handle fitting, the pitch of said threaded portion being adapted to move said fitting into frictional engagement with said disks in response to a force tending to unwind cable from the drum, a pawl mounted on said pin and being biased into engagement with said ratchet disk to prevent rotation thereof in the cable unwinding direction, a handle for actuating said sun gear through said brake mechanism, means connecting said handle to said fitting, said connecting means being adapted to lock said disks and fitting with respect to each other, and a casing cooperating with said drum to enclose said gears and said brake mechanism.

4. In a winch, a frame having a drum shaft non-rotatably mounted therein, a cable drum rotatably mounted on said drum shaft, a ring gear fixed with respect to said drum, a drive shaft rotatably mounted in said frame and having a sun gear mounted thereon, a planetary gear rotatably mounted on said drum shaft and engaging said sun gear and said ring gear, a handle for actuating said drive shaft to rotate said drum in a cable winding direction, self-locking brake means between said handle and said drive shaft, said brake means preventing unwinding of the cable from said drum when the speed of rotation of said handle is less than that of said drive shaft, means for rendering said brake means inoperative, and means preventing normal operation of the winch while said brake means are inoperative.

5. In a hand-operated winch, a frame having a drum shaft and a crank shaft mounted therein with aligned axes, a winding drum mounted on said drum shaft and having a ring gear mounted thereon, a sun gear mounted on said crank shaft, a manually operated handle adapted for rotating said crank shaft, self-locking means between said handle and said crank shaft for forming a driving connection therebetween, said self-locking means being responsive to a force tending to unwind cable from said drum to prevent drum rotation in the cable unwinding direction, a planetary

gear rotatably mounted on said drum shaft and engaging said sun gear and said ring gear, and a casing cooperating with said drum to enclose said gears and said self-locking means.

6. In a hand-operated winch, a frame having a winding drum mounted therein for rotation in either direction, a crank shaft mounted in said frame, a handle adapted for actuating said crank shaft, means for transmitting rotational movement of said crank shaft to said drum, self-locking means forming a driving connection between said handle and said crank shaft and being operative in response to a force tending to unwind cable from said drum to prevent drum rotation in the cable unwinding direction, and means for rendering said self-locking means inoperative to allow the cable to be stripped freely from the drum.

7. In a hand-operated winch, a frame having a winding drum rotatably mounted therein, a crank shaft mounted in said frame, a handle for actuating said crank shaft, means responsive to a force tending to unwind cable from said drum to prevent drum rotation in the cable unwinding direction and to form a driving connection between the shaft handle and said crank shaft, first stop means mounted on said frame and cooperating with said handle to prevent rotation of said handle in the unwinding direction and being movable to a position permitting rotation in the unwinding direction, second stop means cooperating with said drum for preventing rotation of the drum in the unwinding direction, both of said stop means being biased to their operative positions and being movable to their inoperative positions by movement of one of said stop means to its inoperative position.

8. In a hand-operated winch, a frame having a winding drum rotatably mounted therein, a crank shaft, a handle for actuating said crank shaft, means responsive to a force tending to un-

wind cable from said drum to prevent drum rotation in the cable unwinding direction and to comprise a driving connection between the shaft and the handle when the handle is rotated to wind cable onto the drum, first stop means biased to an operative position preventing handle rotation in the cable unwinding direction and being movable to a first inoperative position when said handle is moved in the cable winding direction,

10 15 second stop means biased to a normal position preventing drum rotation in the cable unwinding direction and being movable to another position permitting unwinding rotation of the drum when the first stop means are moved to a second stop position.

9. In a hand-operated winch, a frame having a winding drum rotatably mounted therein, a crank shaft mounted in said frame, a handle adapted for actuating said crank shaft, means for transmitting rotational movement of said crank shaft to said drum, self-locking means forming a driving connection between said handle and said crank shaft and being responsive to a force tending to unwind cable from said drum to prevent drum rotation in the cable unwinding direction, means for rendering said self-locking means inoperative, and means for preventing actuation of the drum in a cable winding direction when said self-locking means are inoperative.
